(57) **CLAIM**

The ornamental design for a mini bar, as shown and described.

DESCRIPTION

FIG. 1 is a right-side perspective view of a mini bar showing my new design;

FIG. 2 is a perspective left-side view of the mini bar shown in FIG. 1;

FIG. 3 is a front view of the mini bar shown in FIG. 1;

FIG. 4 is a rear view of the mini bar shown in FIG. 1;

FIG. 5 is a right-side view of the mini bar shown in FIG. 1;

FIG. 6 is a left-side view of the mini bar shown in FIG. 1;

FIG. 7 is a top view of the mini bar shown in FIG. 1; and,

FIG. 8 is a bottom view of the mini bar shown in FIG. 1.

The broken lines in FIG. 4 showing various connections and coils on the back surface are for illustrative purpose only and form no part of the claimed design.
